UNITED STATES PATENT OFFICE.

THURE LARSSON, OF WORCESTER, MASSACHUSETTS, ASSIGNOR TO NORTON COMPANY, OF WORCESTER, MASSACHUSETTS, A CORPORATION OF MASSACHUSETTS.

CONTINUOUS DRYING KILN AND METHOD OF DRYING WARE.

Application filed October 30, 1920. Serial No. 420,606.

To all whom it may concern:

Be it known that I, THURE LARSSON, a citizen of the United States of America, residing at Worcester, in the county of Worcester and State of Massachusetts, have invented certain new and useful Improvements in Continuous Drying Kilns and Methods of Drying Ware, of which the following is a full, clear, and exact specification.

My invention relates to the art of drying green ceramic articles and more particularly to a progressive drying kiln structure and a method of drying ceramic ware therein.

In the manufacture of ceramic ware, such as a grinding wheel, it is customary to make a plastic mixture of the abrasive grain and clay materials with water, shape this mixture in a mould and then fire it in a kiln to vitrify or fuse the clay materials into bonding contact with the abrasive granules. It has been found that before the articles can be subjected to high heat, the moisture which has been added to give desirable plasticity to the moldable mass must be removed, in order to prevent the fragile wheel structure from being cracked or otherwise injured. The methods heretofore employed in this art have involved placing the green wheels on fixed racks in a steam heated drying room, but no adequate provisions have been made for carefully regulating the temperature and humidity conditions of the drying atmosphere and otherwise insuring that successive consignments of wheels be subjected to the same drying operation in order that uniformity in results may be obtained.

The principal objects of my invention are to improve and simplify the procedure of drying ware, such as green ceramic articles, to eliminate unnecessary manual control of dry room operations and render the drying process substantially automatic in its action, thus obviating accidental variations in the humidity and temperature conditions of the drying air, to provide a method of drying whereby all ware may be subjected to substantially uniform initial and final treatments and to avoid using the expensive procedure heretofore employed for conditioning the drying air in a continuous drying kiln.

With these and other objects in view, as will be readily apparent in the following

disclosure, my invention resides in the combination of parts and the steps of a process as set forth in the description and covered by the claims appended hereto.

In the drawings in which like reference numerals indicate like parts:

Figure 1 is a perspective view partly in section of one form of tunnel kiln embodying my invention;

Fig. 2 is a sectional detail of the air inlet pipes and damper mechanism;

Fig. 3 is a transverse section of the kiln near the ware entrance;

Fig. 4 is a longitudinal section of the kiln partly broken away, taken on the line 4—4 of Fig. 3, to show the entrance and exit portions of the kiln;

Fig. 5 is a horizontal plan partly in section showing the arrangements of the fans, heaters and thermostat controlling devices;

Fig. 6 is a diagrammatic sketch of the arrangement of the thermostats and the dampers and steam pipes controlled thereby.

In accordance with my invention, I propose to dry wet articles, such as green grinding wheels, by passing them progressively through a drying kiln on suitable vehicles and subjecting them initially as they progress to circulating air currents of high temperature and practically 100% humidity in order to heat the articles to a drying temperature without permitting drying action to take place; then to treat them with air currents which are of progressively decreasing temperatures and moisture content and finally to dry them in an atmosphere which is maintained at a constant temperature and is provided with a practically uniform moisture content, whereby all the ware will be dried under the same conditions.

To effect this procedure, I pass the green ware in one direction through the kiln and the circulating drying air in the opposite direction, and in order that the goods may be subjected under uniform conditions to large volumes of heated air, I propose to circulate the air in the dry room in contact with the ware and regulate its forward movement in accordance with its drying capacity and effect upon the ware. This circulating and forward movement may be obtained by causing the air to move repeatedly in a circuitous path transversely of the dry room.

and through a return passage and to progress in a slow helix-like motion endwise through the kiln while thus circulating transversely. Furthermore, in order that the 5 water content of the circulating air entering the dry room may be properly regulated, I propose to utilize the moisture evaporated from the wheels themselves by mixing saturated air drawn from the gas exit with a 10 suitable amount of drier air from the outside atmosphere, as determined by the conditions of humidity at the particular time of operation and thus avoid such variations in drying action as would be caused by 15 climatic changes. To obviate the necessity for manual control of the kiln and to provide for uniform temperature and humidity conditions, I may utilize thermostatically controlled heaters located at intervals through 20 out the kiln, and circulate the air thereover at a uniform rate by suitable means. The rate of progress of the air through the dry room, or the pitch of the helix as it were, is determined by the condition of the drying 25 air and is regulated automatically if desired by thermostatically operated dampers so that if the air is not saturated at the gas exit the longitudinal movement of the air will be retarded while its trans- 30 verse motion is maintained. In this way, the ware will always be subjected to drying currents of air of substantially uniform velocity, but of variable absorption capacity as may be found suitable to give proper drying 35 action to different batches of ware.

In order that this invention may be clearly understood, reference is to be had to the drawings in which I have illustrated one embodiment of this invention. The kiln 40 10, which may be constructed of any suitable material and in accordance with any approved architectural plan, is provided with parallel sets of tracks 11 upon which cars 12 of suitable design may run for transporting the goods through the kiln. To provide for a transverse circulation of the heated air, intermediate partitions 13 and 14 spaced from the side walls 15 and 16 respectively are built to extend the length of the kiln 45 50 from the floor 17 to a false ceiling 18 spaced from the top 19 of the kiln, thereby affording an air passage about three sides of the inner drying room. The circuit of the air is completed, in the form illustrated, by 55 means of a series of spaced openings 20 and 21 formed in the partitions 13 and 14 respectively, these openings preferably being opposite each other and of such sizes as to permit the air currents to travel as uniform- 60 ly as possible in parallel paths through the kiln room. The air is circulated by means of a series of suitably located fans 23, 24 and 25, which may be mounted in the openings 21 with the blades facing outwardly to draw 65 the air from the room and direct it into the

return passage above the drying room. These fans, the construction of which is no part of my invention, may be suitably mounted to be driven from shafts 26 projecting through the outside wall of the kiln, 70 which in turn are driven by pulleys and belting from an outside shaft 27 connected with any desired source of power. By connecting all of the fans with the one drive shaft I insure a uniform draft throughout 75 the drying room.

In order to heat the circulating air currents to different temperatures at different parts of the kiln, I provide a series of independently controlled heaters spaced longitudinally of the kiln and preferably located in the openings 20 so that all the moving air must come into close proximity with the heating elements. Each heater may comprise, as shown, a set of steam pipes 28 connected with an outside source of steam through the transverse pipe 29, the inflow of steam to these pipes being separately regulatable.

With the construction so far explained, 80 the air may be circulated repeatedly transversely of the drying room so that the ceramic ware may be exposed to a drying current of the same air for a desired length of time. A forward motion is given to the 85 air by causing it to travel in a helical path, as it were, and the pitch of the helix may be varied to regulate the rate of flow. To this end, I provide inlet and outlet openings to 90 and from the kiln and means to move the 100 air therethrough. In order to regulate the air flow, I preferably have two separate exits 105 opposite the fan 24 near the ware entrance of the kiln, one to the outside air and the other communicating through a return pipe with the air inlet to the kiln. One exit passage 31 is formed by providing a baffle plate 32 opposite the fan 24 between the walls 14 and 16. That portion of the fan opening 110 beneath the baffle communicates with a passage 33 extending to the ware exit end of the kiln, this passage being formed by a wall 34 built between the kiln walls 14 and 16 and spaced from the floor 17. An open ended pipe 35 passing through the kiln wall 115 to the fan opening above the baffle plate 32 furnishes egress directly from the drying room to the outside atmosphere. The capacity of these exits is considerably less than that of the fan opening, in order that a portion 120 only of the circulating gas may be discharged from the kiln and the remainder be forced to repeat its transverse motion through the dry room. It will be noted that 125 arrows are shown in Fig. 5 to represent the air currents diagrammatically, those in full lines indicating the general direction which the air travels in going through the ware, and the dotted lines indicating the return of 130 the air through the external passages.

The passage 33 connects at its other end through a vertical pipe 41 with the passage between the walls 18 and 19 adjacent the end fan 25, whereby moist air from the fan 24 and opening 31 may be returned to the kiln. Air may also be drawn into the drying room through the conduit 42 which opens to the external atmosphere. A 3-way passage formed at the junction of the passage 33 with the pipes 41 and 42 may be controlled by a suitable damper to permit the introduction into the kiln room of desired proportions of water saturated air and the drier air from the external atmosphere. The damper may be formed, as illustrated in Fig. 2, of a member 43 having a surface like a portion of a sphere which is mounted to swing about the pivot 44 in the axis of pipe 41 and have its position controlled by means of a suitable crank 45 on the end of the pivot outside the pipe operated by a thermostat device to be presently described. The ends of the conduits at the junction are suitably shaped relative to the form of the damper so that the damper may close off either the passage 33 or the pipe 42 or leave each partially open. The pipe 35 is also provided with a suitably shaped damper 46 which is pivotally hinged within the pipe and may be controlled by means of the crank 47 to close off entirely the opening to the external atmosphere or permit a portion of the gas issuing through the end fan 24 to pass outside of the kiln. If it is desired that my method be carried on automatically so that the temperature and humidity conditions in the kiln room need not be manually controlled, I provide a series of thermostats which are exposed to the kiln atmosphere at various points, for controlling each heater and the dampers 43 and 46. While various types of thermostats may obviously be employed, I have illustrated, somewhat diagrammatically, a well known pneumatic type which comprises two sets of heat measuring instruments, one a wet bulb thermometer 51 and the other a dry bulb thermometer 52. Each wet bulb thermometer is kept moistened by suitable means, such as a wick 53 surrounding the thermometer and dipping in a receptacle 54 which is supplied with water. These thermostats, as will be understood by one skilled in the art, comprise control instruments 55 which are each adapted to be set for any temperature within the desired range, whereby, when the particular temperature has been reached, compressed air from the supply pipe 56 will flow through the thermostatically controlled valves in the instrument to a device 57 adapted to operate the valves in the steam pipes 29 or the air dampers 43 and 46. This device 57 comprises in general a stem 58 connected at one end with an inside diaphragm and at the other with the valve in the steam pipe or the damper operating linkage, where-

by air pressure admitted through the pipe 59 may operate this diaphragm and move the stem 58 outwardly, the return movement being caused by a helical spring surrounding the stem 58. 70

As shown particularly in Fig. 6, the two end wet bulb thermostats 60 and 61 are utilized to operate the dampers 43 and 46. The two end steam pipes 29 supplying the two end steam heaters in the tunnel kiln are operated by the dry bulb thermostats 62 and 63, while the remaining steam heaters supplied by the remaining steam pipes 29 are controlled by thermostats in which the dry and wet bulbs 51 and 52 have a combined effect, that is the wet bulb thermometers control the humidity conditions in the different parts of the drying room and the dry bulb thermometers the temperatures. The mechanical connections between the end thermostat 60 and the damper 43 may be of any suitable construction but, as illustrated particularly in Fig. 2, may comprise a bell crank lever 64 pivoted at 65 to a fixed member, one end of this lever being connected to the valve stem 58 and the other to the damper operating linkage 66. The air passes from pipe 56 through the thermostatic device and through pipe 67 to the valve control mechanism 57. The damper 46 in pipe 35 may be controlled similarly, as shown in Fig. 3, the air passing through pipe 68 from the wet bulb thermostat 61 to the valve control mechanism, in which the stem 58 connects through a linkage with the damper crank 47. 100

In order that the kiln may be closed to external atmospheric conditions, I provide suitable doors, such as the sliding doors 70, at each end of the kiln. The cars are loaded and unloaded outside of the kiln. While the mechanical constructions of these loading and unloading mechanisms are not a part of my invention, they may comprise, as shown in Fig. 4, suitable uprights 71 and 72 supporting a travelling crane 73 for lifting the ceramic articles and an endless chain mechanism 74 at the ware entrance which is adapted to engage a dog 75 on the car and push it into the kiln, this chain being moved by any desired type of motor. A portion only of this external construction is shown at the exit end of the kiln in Fig. 4. I have furthermore illustrated the ceramic articles as grinding wheels which are supported on separate batts 76 spaced apart so that air may be freely circulated between and around the wheels. If desired, the carriers 77 for these batts may have legs 78 to permit movement by means of motor trucks. Two of these carriers may be placed on the car, one being supported directly on the car body and the other above the first on legs 79 attached to the car. 110

In accordance with my invention, the kiln

is so operated that the air at the left hand end of the kiln (Fig. 4) where the ware enters is saturated with moisture and held at a uniformly high temperature which, for example, may be considered to be 120° F. In order that the ware leaving the kiln may be exposed to air of uniform drying characteristics, the temperature of the entering air is held at a lower temperature, for example 100° F., and the humidity of this air so controlled that it has a substantially constant moisture content, as, for example, 0.03 pound of water per cubic foot of air. To provide automatic regulation for the humidity conditions, the wet bulb thermostat controlling the damper 46 is so set that the damper shall be closed to the external atmosphere until the wet bulb temperature is about that which represents a saturated condition of air for 120° F. At the right hand end of the kiln where the air enters, the damper 43 is similarly controlled by the wet bulb thermostat, so that if the latter is set for a temperature of, say, 89° F., which represents approximately a humidity condition of 70% for 100° F. dry bulb temperature, and if the temperature of the wet bulb thermostat rises above 89° F., thus indicating that the moisture content is increasing, the thermostat operates to close off the passage 33 and open the entrance to pipe 42 so that drier air will be drawn from the external atmosphere. As a result, and since the first heater at this end of the chamber is controlled by the dry bulb temperature to maintain a temperature of 100° F., the humidity condition of the air will fall and the wet bulb thermostat will become lower in temperature and so operate to open the damper again to the passage 33 and close it to the outside air through pipe 42. This damper will thus hunt or swing back and forth to regulate the condition of the entering air to give substantially a constant amount of water per cubic foot of air entering the dry room.

The condition of the air opposite each of the intermediate heaters is regulated by the independent thermostatic device so that the moisture content of the air progressing through the dry room is gradually increased by the drying ware until it becomes a maximum about four or five heaters from the ware entrance. The drying operation results from the fact that the air while increasing in moisture content as it moves along is being heated to a higher temperature to keep it below the saturation point. If the water content of the whole kiln is too low, as when the drying operation is started, the dampers 43 and 46 close the passages to the external atmosphere so that no air can leave or enter the kiln and the air must circulate longitudinally of the kiln and through the return passage 33 until it be-

comes sufficiently moist. At other times, the rate of flow of the air longitudinally of the kiln varies from zero to a maximum depending upon the positions of the two dampers, it being noted that if damper 46 closes pipe 35 the forward movement of the air is permitted only when damper 43 swings to let a little more moisture into the entering air. Hence, irrespective of the type of ware being dried or the variable humidity and temperature of the external atmosphere, the drying air is so conditioned as to give substantially the same treatment to the ware throughout the changing seasons.

Having thus described my invention, what I claim as new and desire to secure by Letters Patent is:

1. The method of drying ware comprising continuously moving ware to be dried through a drying kiln, passing drying air over the ware at a uniform velocity, and regulating the rate of flow of air passing through the kiln to maintain the same properly conditioned to give a desired drying action.

2. The method of drying ware comprising passing the ware progressively through a kiln, circulating conditioned air in one direction over the ware and back in a substantially helical path and varying the forward movement of the air through the kiln to control its drying action on the ware.

3. The method of drying ware comprising continuously moving the ware through a drying kiln, repeatedly circulating heated air over a given piece of ware, moving the air longitudinally through the kiln, progressively heating the air in its forward movement, and regulating the rate of its longitudinal flow so as to subject the continuously moving ware to air containing predetermined amounts of moisture at definite localities in the kiln.

4. The method of drying ware comprising passing the ware progressively through a dry room in one direction, moving a heated air current in the opposite direction in contact with the ware, repeatedly circulating the drying air in contact with a given piece of ware and varying the rate of flow of the air through the dry room to regulate the moisture content of the air and the rate of drying.

5. The method of drying ware comprising passing air progressively through a kiln in one direction, passing the ware in the opposite direction, progressively heating said air in its passage through the kiln, repeatedly circulating kiln air of a given temperature over a piece of ware to increase its drying action thereon, regulating the rate of air movement through the kiln so that the air will have a predetermined moisture content at the ware entrance, and maintaining a

substantially uniform moisture content in the air at the ware exit to subject successively treated batches of ware to a substantially uniform drying treatment.

5. 6. The method of drying ware comprising passing the ware progressively through a drying kiln, repeatedly circulating heated air at a uniform velocity in contact with the ware, moving the circulating air forward through the kiln in a direction opposite to that of the ware and varying the rate of such forward movement so as to keep the air saturated at the ware entrance and thereby heat the ware initially without drying it.

7. The method of drying ware comprising passing the ware progressively through a drying kiln, repeatedly circulating heated air at a uniform velocity in contact with the ware, moving the circulating air forward through the kiln in a direction opposite to that of the ware at such a rate as to keep the air saturated at the ware entrance and thereby heat the ware initially without drying it and maintaining the moisture content of the heated air entering the kiln at a substantially constant amount.

8. The method of drying ware comprising passing the ware in one direction through a drying kiln, moving a body of air over the ware in the opposite direction, progressively raising the temperature of the air as it travels through the kiln, repeatedly circulating the air over the ware to increase its drying action until the air has a fixed moisture content at the ware entrance returning kiln air from the air outlet to the air inlet and maintaining the temperature and humidity of the entering air constant to subject successively treated wares to the same drying treatment.

9. The method of drying ware comprising passing the ware progressively through a drying kiln in one direction and a drying air in the opposite direction, circulating the air at a uniform velocity over the ware, heating the entering air and maintaining its moisture content substantially uniform, progressively raising the temperature of the air to a desired maximum as it passes through the kiln and maintaining the air throughout an extensive zone adjacent the ware entrance in a substantially saturated condition to heat the ware initially without drying it.

55. 10. The method of drying ware comprising passing the ware progressively through a drying kiln in one direction and a heated air current in the opposite direction, maintaining the entering air at a substantially uniform temperature and moisture content, progressively heating the air as it passes through the kiln, regulating the temperature of the air at the ware entrance to a substantially uniform degree higher than that of the entering air and moving the air

through the kiln at such a rate as to keep the air saturated at the ware entrance and cause the ware to be heated initially without being dried.

11. The method of drying ware comprising passing the ware in one direction through a kiln and heated air over the ware in the other direction, progressively raising the temperature of the air as it passes through the kiln, independently regulating the temperatures of the air at spaced points in the kiln to maintain a desired drying rate at each point, circulating the air through the kiln at such a rate as to maintain a uniform humidity condition at the ware entrance and regulating the temperature and humidity of the air at the ware exit to provide a substantially uniform drying treatment for successive batches of ware.

12. The method of drying ware comprising passing the ware progressively through a drying kiln in one direction and a heated air current in the opposite direction, repeatedly circulating the heated air current adjacent a piece of the ware transversely of the kiln, moving the air longitudinally of the drying kiln at such a rate as to keep the air saturated at the ware entrance and thereby heat the ware initially without drying it and progressively heating the air current as it moves through a portion of the kiln.

13. The method of drying ware comprising passing the ware progressively through a drying kiln, passing a heated current of air in the opposite direction, maintaining the air at the ware entrance in a saturated condition to heat the ware initially without drying it, returning a portion of the moisture laden air to the opposite end of the drying kiln and conditioning the air entering the kiln to provide it with a substantially uniform moisture content.

14. The method of drying ware comprising passing the ware at a uniform rate through a drying kiln, moving a heated current of air in the opposite direction in contact with the ware, mixing a moisture saturated air with air from the outside atmosphere to provide a substantially uniform moisture content for a fixed temperature condition, passing this air into the kiln for the final drying operation, progressively heating this air as it passes through the kiln to cause the ware to be dried and varying the rate of flow of the air through the kiln to maintain a uniform humidity condition adjacent the ware entrance.

15. The method of drying ware comprising passing the ware progressively in one direction through a kiln and drying air in the opposite direction, heating the air as it passes through the kiln, withdrawing the moisture-laden heated air and returning a portion of the same to the ware exit, mixing unsaturated air therewith and conditioning

the mixture as required to provide an initial drying current of uniform temperature and moisture content.

16. The method of drying ware comprising passing the ware progressively in one direction through a kiln and drying air in the opposite direction, heating the air as it passes through the kiln, regulating the kiln conditions to provide a saturated air of a substantially uniform temperature at the ware entrance, returning a portion of this heated saturated air to the ware exit, mixing unsaturated air therewith and conditioning the mixture to provide an initial drying air of substantially uniform temperature and absorption capacity.

17. The method of drying ware comprising passing the ware progressively through a drying kiln, passing a heated current of air through the kiln in the opposite direction, repeatedly circulating the air at a uniform velocity transversely of the kiln through the ware, returning a portion of the moisture laden air to the air entrance, mixing this moisture bearing air with air from the external atmosphere and conditioning the same to maintain a substantially uniform moisture content at a fixed temperature, progressively heating the air current in the kiln and maintaining a substantially saturated condition adjacent the air exit of the kiln to heat the ware initially without drying it.

18. A drying kiln comprising a room having an air outlet and an air inlet, means for conveying material therethrough, means to circulate heated air in the room at a uniform velocity and means for varying the rate of flow of the circulating air lengthwise through the kiln from the inlet to the outlet to regulate the moisture content of the air and the rate of drying.

19. A continuous drying kiln comprising a room, an air inlet and an air outlet at opposite ends of the kiln, means to heat a supply of air for said kiln, means to circulate the air at a uniform velocity repeatedly transversely of the drying room and means to move the air longitudinally through the kiln at a variable rate or to prevent such movement.

20. A continuous drying kiln comprising a room having air inlet and outlet openings, a series of heaters within said kiln, means to circulate air transversely of the kiln at a uniform velocity and repeatedly in contact with said heaters and means to move the circulating air at a variable rate longitudinally through the kiln.

21. A continuous drying kiln comprising a room having closures at its ends and a passageway for conveying ware therethrough, means to circulate air past said ware, controllable heating devices in said kiln, means to maintain the moisture content of the air entering the kiln room at a uni-

form amount and means to vary the rate of flow of the air through the kiln to subject the ware entering the kiln to a drying atmosphere of substantially uniform moisture content and of a high temperature.

22. A continuous drying kiln comprising a room having closures at its ends and a passageway for conveying ware therethrough a series of independently controlled heaters spaced in the kiln, means to circulate air repeatedly transversely of the room in contact with said heaters and the ware, thermostatic devices to regulate said heaters and means comprising regulatable inlet and outlet openings to and from the kiln to cause a controllable drift of the transversely circulating air from one end of the kiln to the other.

23. In a continuous drying kiln, a series of independently controlled heaters arranged along one side thereof, means including fans to circulate air transversely of the kiln and through said heaters, thermostatic devices cooperating with said heaters to control the temperature and humidity conditions in the intermediate portion of the kiln, means providing inlet and outlet openings at opposite ends of the kiln and means, including a thermostatic device, to move the air longitudinally of the kiln at a variable rate to regulate the humidity condition of the air adjacent the exit.

24. In a continuous drying kiln, a room having closures at its ends and a passageway for conveying ware therethrough, a series of independently controllable heaters in the dry room, means to circulate air through the heaters and in contact with the ware, means providing air inlet and outlet openings to and from the dry room, a passage to the external atmosphere and a return passage from the outlet to the inlet opening and regulatable means for mixing the return air with fresh air to provide the entering air with a constant moisture content.

25. A continuous drying kiln comprising a room having closures at its ends and a passageway for transporting ware therethrough, a series of heaters in said kiln, means for circulating air repeatedly transversely of the room in contact with said heaters and the ware, means providing air inlet and outlet passages from the kiln to the external atmosphere and a return passage between the outlet and the inlet openings, means including controllable dampers cooperating with said passages to move the air longitudinally through the kiln at a variable rate and to condition the air entering the kiln and means including thermostats to control the amount of heat admitted to the heaters in order to regulate the humidity conditions in the room.

26. In a continuous drying kiln, a series of thermostatically controlled heaters arranged

70

- longitudinally therein, means comprising a series of fans to circulate the air transversely through the kiln and over said heaters repeatedly, means providing air inlet and outlet openings at opposite ends of the kiln, means to move the circulating air longitudinally through the kiln, means including a wet bulb thermostatic device to retard the flow of air through the kiln until it becomes substantially saturated at the exit and a wet bulb thermostatically controlled device to provide the air entering the kiln with a constant moisture content.
27. In a continuous drying kiln, a series of independently controlled heaters arranged along one side of the kiln longitudinally thereof, a series of fans disposed opposite said heaters and cooperating partitions to circulate the air through the heaters and transversely of the kiln, means providing air inlet and outlet openings at opposite ends of the kiln, means tending to circulate the air longitudinally of the kiln room and means to vary the rate of movement of the air longitudinally through the room to provide uniform humidity conditions at a given location in the kiln.
28. In a continuous drying kiln, walls therein forming an inner dry room extending longitudinally of the kiln and a return passage outside of the room, the vertical walls having openings disposed opposite each other, heaters in the openings on one side of the kiln room, means to regulate the heaters independently, fans in the openings on the other side to circulate the air transversely of the kiln room and through the return passage repeatedly and means providing regulatable inlet and outlet openings at the opposite ends of the kiln for varying the rate of flow of the air through the kiln.
29. In a continuous drying kiln, longitudinally extending partitions forming an inner dry room and return passage thereover, the vertical partitions having openings disposed opposite each other, heaters in the openings on one side of the room, fans located in the openings on the other side for circulating the air transversely of the room and through the return passage repeatedly, means providing inlet and outlet passages at opposite ends of the kiln, a passage to the external air and a return passage from the outlet to the inlet, means to move the air lengthwise of the kiln and through the return passage to the inlet and regulatable dampers cooperating with said passages to vary the rate of movement of the air lengthwise of the kiln and to condition the air entering the kiln by mixing the returned humid air with fresh air from the external atmosphere.
30. In a continuous drying kiln, a series of heaters arranged longitudinally thereof, thermostatically controlled devices to regulate said heaters independently of each other, means including fans to circulate the air transversely of the dry room repeatedly in one direction, means providing inlet and outlet openings to and from the kiln to the external atmosphere and a return passage from the outlet to the inlet opening, means for circulating the air longitudinally of the kiln and the return passage to the inlet opening and a thermostatically controlled device to regulate the forward movement of the repeatedly circulating air in said kiln and to condition the air entering the kiln by mixing the return air with fresh air to obtain a fixed moisture content.

Signed at Worcester, Massachusetts, this 28th day of October, 1920.

THURE LARSSON.
